W. P. HUNT

MULTIPLE SPINDLE DRILL

Filed June 30, 1926

UNITED STATES PATENT OFFICE.

WILSON P. HUNT, OF MOLINE, ILLINOIS, ASSIGNOR TO MOLINE TOOL COMPANY, OF MOLINE, ILLINOIS.

MULTIPLE-SPINDLE DRILL.

Application filed June 30, 1926. Serial No. 119,593.

My invention has reference to multiple spindle drills, and has for its chief purpose to increase the simplicity and efficiency of such machines. On account of the fact that the drills which are used in these machines are frequently of different lengths, and that the work frequently calls for the boring of holes of different depths, it has been found to be desirable to support the drills so that they could be adjusted vertically. This has usually been provided for by supporting the bearing for the spindle so that it could be adjusted with relation to the supporting arm. This has not been easy of accomplishment on account of the fact that it is necessary to connect the bearing and arm by at least two bolts, one of which was not readily accessible when it was desired to make an adjustment. In the present invention the spindle bearing is provided with a separate bushing or sleeve, which carries the spindle, and this bushing is arranged for adjustment vertically in a very simple and effective manner, somewhat similar to micrometer adjustments.

Another object of the invention is to so construct the device that it will be possible to have the supporting arm and spindle bearing rigidly united, and do away with the bolts by which said parts have usually been connected, and by means of which the adjustments have heretofore been made.

Another purpose thereof is to so construct the device as to make it possible to make the necessary adjustments by the use of a single operative part, which is readily accessible for operation by a wrench or similar tool, even when the drills are positioned in close proximity to each other.

Another object thereof is to provide means for preventing the parts from getting out of adjustment, so that there is no danger of a disturbance of the set-up, after the same has been made.

The above-named, and other features and advantages of the invention will more fully appear from the following specification, taken in connection with the accompanying drawings, in which;

Fig. 1 is a longitudinal section of a drill supporting arm and mechanism supported thereby.

Fig. 2 is a plan view of the forward end of the arm, with a cross-section through the upper end of the spindle.

Fig. 3 is a detail of the plate 18.

Fig. 4 is a side elevation of the upper part of the bushing 5.

Fig. 5 shows another form of locking means for the shaft 13, in section.

The reference number 1 indicates a drill head, to the lower face of which is secured a slotted arm 2, by means of a bolt 3. At the outer end of the arm 2 is a boxing 4, which in the present construction is formed in the end of the arm by extending a vertical bore therethrough. In said bore is held a bushing 5, having its upper end threaded to correspond with a thread in the upper part 70 of such bore, as indicated at 6, the thread on the bushing being shown at 7. By rotating said bushing it is caused to move upwardly or downwardly in said bore, as desired.

Rotatably mounted in the bushing 5 is a spindle 8, threaded at its upper end to receive a pair of nuts 9. On the lower end of said spindle is a drill holder 10. The upper end of the bushing 5 is also channeled, forming elongated teeth 11 thereon, which teeth are engaged by the teeth of a gear-wheel 12 on the end of a shaft 13, rotatable in a smaller bore in the arm 2, the lower end of said shaft being squared to 85 form a wrench hold, whereby the shaft may be rotated, the movement thereof being imparted to the bushing 5, to give rotation thereto. The shaft 13 is also formed with a square shoulder as shown at 16, such shoulder being fitted to enter an aperture 17 of similar size and shape in a plate 18 fixed to the lower side of the arm 2. When in this position the shaft 13 is held from rotation.

Upon a wrench being applied to the squared head of the shaft 13 the initial force thereof serves to move the shaft upwardly, permitting the shaft to rotate freely, and by the rotation of said shaft and the wheel 12 thereon, such movement is imparted to the bushing 5 and spindle therein, moving the same upwardly or downwardly, as desired. By providing threads of a proper pitch on the bushing the movement thereof may be made a very gradual one, so as to 100 secure close adjustments of the drill held in

the spindle. After the desired adjustment of the spindle has been made the shoulder 16 is worked into the opening 17 again, and the shaft 13 and bushing 5 locked from further movement.

At the upper end of the spindle 8 is shown a universal joint 19, of common form, by means of which the spindle may be connected with an operating shaft.

It will be observed that the shaft 13 is almost entirely out of the way, at the rear of the spindle, and in a position easy of access for an operating tool. The space occupied by said shaft and its projecting end 15 is so limited that even when the spindles are grouped in close proximity to one another, there is ample room for said operating devices.

In Fig. 5 is shown another means for locking the shaft 13 from movement, the seat in the arm 2 for the wheel 12 being provided with a pin 20, adapted for engagement with the teeth of said wheel, when the shaft is in its lowest position. By this arrangement the shaft can be locked by a relatively less amount of rotation than by the use of the

shoulder 16, which would be dispensed with in the present arrangement.

It will be observed that the teeth of the wheel 12 will be in mesh with the gearing 30 on the bushing 5 in any position that the bushing is in, vertically.

What I claim, and desire to secure by Letters Patent, is:

In a device of the class described, a spindle supporting arm, a bore in the end thereof fitted with screw threads, a bushing rotatable in said bore, adapted for the support of a spindle, and exteriorly threaded to correspond with said first-named thread, gearing on said bushing, a shaft rotatably mounted in said arm, and capable of vertical movement therein, a gear-wheel on said shaft in mesh with the gearing on said bushing in all relative positions of the bushing and shaft, and means for locking said shaft from rotation when at its lowest point, the initial operation of said shaft lifting it from a locked position, and the next operation giving rotation thereto.

In testimony whereof I affix my signature.

WILSON P. HUNT.
